Primary Examiner — Kelley Donnelly(74) *Attorney, Agent, or Firm* — Dwayne E. Rogge; Schacht Law Office, Inc.(57) **CLAIM**

The ornamental design for a mesh serving tray, as shown and described.

DESCRIPTION

FIG. 1 is a top isometric view of the mesh serving tray thereof. FIG. 2 is a top view thereof.

FIG. 3 is a side elevation view with the opposing side view being a mirror image thereof.

FIG. 4 is a front elevation view with the opposing rear view being a mirror image thereof.

FIG. 5 is a bottom view thereof.

FIG. 6 is a bottom isometric view thereof.

FIG. 7 is a top isometric view thereof with a cup portion removed for clarity of illustration.

FIG. 8 is a top plan view thereof with a cup portion removed for clarity of illustration.

FIG. 9 is a sectional view taken along line 9-9 of FIG. 8; and, FIG. 10 is a bottom isometric view thereof with a cup portion removed for clarity of illustration.

Any broken lines shown in the drawings are for illustrative purposes only and form no part of the claimed design.
